(57) CLAIM

The ornamental design for an infant casket, as shown and described.

DESCRIPTION

FIG. 1 is a perspective view of an infant casket showing my new design;

FIG. 2 is a left end view thereof, the right end view being a mirror image;

FIG. 3 is a top plan view thereof;

FIG. 4 is a right side elevational view, the left side elevational view being a mirror image thereof; and,

FIG. 5 is a bottom plan view thereof;

FIG. 6 is a front perspective view of a second embodiment of an infant casket showing my new design;

FIG. 7 is a left end view thereof, the right end view being a mirror image;

FIG. 8 is a top plan view thereof, the bottom plan view is the same as FIG. 5; and,

FIG. 9 is a right side elevational view thereof, the left side elevational view being a mirror image thereof.
